APPARATUS FOR THE COOKING OF BITUMINOUS OR ASPHALTIC LIQUIDS

Roy S. Petersen, San Antonio, Tex., assignor to
 Brassert-Tidewater Development Corporation,
 Chicago, Ill., a corporation of Delaware

Application February 23, 1934, Serial No. 712,460

2 Claims. (Cl. 202—102)

This invention relates to a new and improved apparatus for the coking of bituminous or asphaltic liquids, pitches, petroleum residues, and other fluid or semi-fluid compounds which may or may not contain entrained solid fuels such as 5 carbon, fine coal or the like.

In prior processes for coking materials of this character closed chambers have been used and vapors preheated to temperatures in excess of 10 850° F. have been admitted into the chambers in contact with the material being treated, which is usually heated to temperatures in excess of 600° F. The coking condition is brought about by mixture of these two heated streams in the 15 chamber with a deposit of the coke formed in the lower portion of the chamber. In vertical chambers of ten foot diameter depositions of coke in excess of thirty feet in height have been carried on in actual operation. When the 20 desired depth of coke has been reached the feed lines are shut off and steam introduced into the chamber until the coke has been cooled below the ignition point. Sections of the chamber wall or bottom are then removed and the coke is 25 withdrawn by mechanical means such, for example, as cables or chains which have been placed in the chamber previous to the coking operation and have become embedded in the mass of coke. In some instances rotary drills are used to break 30 the coke sufficiently to permit its removal. The difficulties of coke removal are increased as the amount of volatile matter in the coke is decreased, since the coking structure becomes denser and harder.

35 My present invention obviates these difficulties by placing the usual steel shell preferably in a horizontal position and building within it, of refractory material, a coking chamber of a shape which facilitates mass removal of the coke without first cooling it and this further serves to retain as much heat as possible by insulating the chamber. In addition to the refractory walls of the chamber proper, other insulating materials 40 may be used between the walls and the shell or exteriorly of metal shell. The two ends of the chamber are equipped with insulated doors which are sealed to the shell proper and are removable when pushing out the hot coke after completion 45 of its formation.

50 The heat for the coking operation is supplied by the admission of hot gases and/or vapors into the chamber in such quantity as to properly coke the available feed. These vapors after 55 accomplishing their purpose are discharged into

suitable fractionating and condensing apparatus along with volatile portions of the feed.

It is an object of the present invention to provide a new and improved apparatus for the coking of materials of the character described. 5

It is an additional object to provide a method whereby the coking operation is carried on without the necessity for the application of external heat to the coking chamber.

It is also an object to provide an insulated 10 horizontal chamber designed for the rapid and economical removal of the formed coke by means of a mechanical pusher or its equivalent.

Other and further objects will appear as the 15 description proceeds.

I have shown certain preferred embodiments of my invention in the accompanying drawing, in which—

Figure 1 is an elevation showing one form of the coking chamber or oven, with the associated 20 quenching car and coke pushing apparatus;

Figure 2 is a cross section taken on line 2—2 of Figure 1;

Figure 3 is a cross section of a somewhat modified form of construction and taken on the line 25 3—3 of Figure 1; and

Figure 4 is a section similar to Figure 2 but showing a cylindrical coking chamber.

In the form of construction shown in Figures 1 and 2, the horizontal metallic shell 12 is supported on piers 13. This shell contains a refractory lining 14 and a refractory floor 15 which define a horizontally extending coking chamber. Doors 16 and 17 are provided to close the ends 30 of the steel shell and the coking chamber. The 35 hoist 18 is provided on the left end of the coking chamber for the purpose of raising and lowering the door 16. Floor extensions 19 and 20 are provided on the opposite ends of the shell for walkways and also for the purpose of supporting 40 coke and coke moving apparatus during the removal of the coke layer.

The quenching car 21, which may be of usual construction, is shown at the left end of the oven. The pusher machine 22 is shown at the right end 45 of the oven, this pusher moving on tracks 23 if it is used in connection with a plurality of similar ovens. The pusher includes a push beam 24 having a pushing head 25, this beam being reciprocated into and out of the coking chamber as desired by means of a motor 26, drive connections 27 and chain or rope 28 which is coupled to the push beam. The pusher machine 22 is also provided with a hoist 29 for use in raising 50

and lowering the door 17 at the adjacent end of the chamber.

The chamber is provided, as best shown in Figure 2, with a heavy hydrocarbon feed passage 30 in its upper portion and an opposed feed passage 31 for use in introducing hot oil vapor or its equivalent which can be used in the coking operation. As shown in Figure 1 the upper portion of the chamber is also provided with an offtake passage 32 which is connected with the offtake header 33 for carrying off the volatile products of the process and for venting the chamber.

The form of construction shown in Figure 3 differs from that shown in Figures 1 and 2 in that the steel shell 40 is oval rather than circular in cross section, which affords a coking chamber 41 having a wider floor 42.

A number of flues 43 are provided below this floor 42 and these flues may serve for the introduction of heated products of combustion, gases and/or vapors or the introduction of gas and air for heating the chamber floor from below.

In carrying out my process by the use of apparatus of the general character, the material being treated will be introduced through the upper portion of the oven through passage 30. This material will have been reduced, if necessary, to a fluid form by heat and will be heated above 600° F. if feasible, and may be forced in under suitable pressure if it contains sufficient solids as not to flow readily under normal conditions. The hot oil vapor or its equivalent introduced through the passage 31 may consist of highly heated vaporized oil and/or heated fixed gases. In one method of carrying out the process a suitable gas oil fraction may be taken off a bubble tower and passed through a preheater where its temperature is preferably raised to above 900° F. This heated oil fraction is then discharged into the oven through passage 31 to serve as a heating medium for carrying out the coking process.

By a method of this character the temperature in the oven need not exceed the temperature of the vapors coming in and therefore destructive heating of the vapors which are used as the heat transfer medium can be largely reduced. It will be understood that other oil vapors and/or fixed gases may be heated and introduced in similar manner.

The form of construction shown in Figure 4 differs only slightly from that shown in Figure 2. It comprises the cylindrical steel shell 50 with the refractory lining 51 which is also cylindrical and affords a cylindrical coking chamber with the arcuate bottom. The feed lines 52 and 53 are provided for introducing the material to be treated and the vapors and/or gases for supplying the heat for treatment.

After a sufficient depth of coke has been formed in the oven the feed of the material being treated is stopped. The feed of the heating medium may also be stopped immediately or may be continued for a period to substantially complete the coking of the last portion of the material introduced.

During the last period vapors are discharged from the oven which correspond to the wax tailings collected at the end of the ordinary shell still coking operation. As these are not desirable for further fractionation, we prefer to vent the oven and gradually introduce air into the oven through suitable openings to burn such undesirable vapors in the oven, thus increasing the temperature of the walls and also at the same time heat the coke charge. If desirable, suf-

ficient air will be admitted to also burn part of the coke and thus reduce the volatile content of that remaining to whatever point may be desired. The additional heat will also have the effect of reducing the friability of the coke and making it a better selling product. The product of this coking and subsequent beehive operation is of a different quality from any now on the market and I also claim this material as a new article of manufacture whose physical properties are much superior to the ordinary chamber coke and in which the volatile matter is maintained at a percentage best suited for domestic use. This will usually be from 3% to 5%.

It will be observed that in my method of operation the coke is not cooled before removal from the oven and, on account of the insulation, the brick work maintains a temperature which corresponds to the coking temperature used in the oven, it building up during the burning off period, thus initiating the coking of the first pitch which is deposited on it. This being the case, the problem of pushing the oven becomes only that of having sufficient power to overcome the friction of the coke with the containing floor and walls. This naturally saves time and thus increases the throughput of a given chamber.

After the desired point is reached the doors are removed and the coke is pushed or drawn by mechanical means such as the pusher shown in the drawing. After the coke is removed the doors are again closed and the operation is repeated. By the use of an approximately flat floor the first push on the hot coke breaks the nearby coke free from the floor and usually causes numerous vertical fractures, sometimes to the extent that the coke will roll up rather than push out in a flat sheet. In this way the mass of coke successively breaks away from the floor. A further advantage of pushing the coke hot is that it breaks up into more suitable sizes when dropping into the coke car than it usually would if it were allowed to cool and be pushed out in a solid mass.

Under some conditions of operation the temperature of the feed material may be such that it is possible to introduce into the chamber a substantial depth of liquid and to thereafter agitate the liquid by passing gases through it to an extent sufficient to initiate coking. The operation may be continued by the addition of more hot charging stock and gases until the desired coking is obtained. If the heat of the charging stock is sufficient, it may be unnecessary to add heat through the gases, which may simply serve for agitation.

It will be recognized that at times the temperature in the top of the oven may be high enough to cause destructive heating of the lighter hydrocarbons in the gases and vapors. Therefore it is one of the purposes of this invention to so control this heat by feeding in the proper amount of the charging stock which is at the lower temperature to reduce the top temperature to a safe point before introducing the heating gases. Likewise, if the top is too cool, more of the heating gases can be introduced and less of the charging stock.

In some special cases it may prove desirable to use the ordinary shell still or vertical coking chamber types, horizontally placed, with or without insulating lining, as shown in Figure 4. In this case the pusher would be made to conform to the curvature of the bottom of the chamber and the coke would be allowed to form to whatever depth was best adapted for pushing the same. In this way, as in the previous ones, the

coke would be preferably pushed hot, as I have found that this method is far preferable to quenching the coke in the chamber and thus reducing the chamber's temperature so materially.

My process fits in very nicely with the ordinary cracking operations of a refinery where the coking chamber is an integral part of the cracking apparatus. If desired, vapors and bottoms can be fed into my coking chamber instead of into the usual evaporators or coking chambers which constitute an integral part of the cracking unit. In this event, my coking chamber would be operated under the regular coking pressure and no liquid residues would be formed as a result of the cracking process.

In the case where charging stock is passed directly through a heater it may be found that the transfer line can be discharged directly into my oven instead of into the usual reaction chamber. In this event the size of the oven would preferably be so proportioned that the soaking or reaction time required for best operation of the cracking unit would be attained in the chamber, which in this case would receive the heavy residue and coke it without further handling. In such an operation a sufficient number of coking ovens would be installed to assure that the operation of the cracking unit would continue without interruption, the stream of vapors being transferred from one coking unit to another as required.

In my method the temperature in the coking oven is not reduced by the quenching of the coke therein, therefore my coking oven is ready to go back on the line immediately upon its being emptied and sealed up again. If its temperature is either higher or lower than that of the charging stock which will be admitted to it I can bring the oven to the desired temperature either by cooling with steam, for example, or raising its temperature by bringing in hot vapors or burning vapors and/or gases in it. This is a very important element of my invention as it relieves the operator of the delicate operation of raising the temperature in the coking chamber to permit the entrance of hot vapors without causing operating difficulties and serious strains on the equipment where the chamber is cooled.

While I have stated that the coke mass is preferably pushed or pulled from the oven while hot, it will be understood that this is not always essential and that under some circumstances it may be desirable to first cool the coke before discharging it.

It will be understood that the process is not limited to the exact form of apparatus shown in the drawing. The form shown in Figure 3 may be used or other means may be provided for heating the floor from below if desired. This heating of the floor may be carried on only when starting up the oven or may be used throughout the process, as desired. It will also be understood that the method itself will be modified to meet varying conditions and requirements, and I contemplate such changes and modifications as come within the spirit and scope of the appended claims.

I claim:

1. Apparatus for coking heavy hydrocarbons in fluid form, which comprises a metallic outer casing entirely surrounding a refractory lining, said metallic casing serving to prevent infiltration of air through said lining, said lining forming a horizontal coking chamber therein, said casing having openings at each end thereof, removable sealing means covering said openings, a substantially flat refractory floor for said chamber and heating flues below the floor and within the metallic casing, means for introducing into the chamber the heavy hydrocarbons to be coked, means for removing from the chamber vapors produced by the coking operation, a pusher ram and means for forcing it through the chamber to push out the coke, and means for receiving the coke after it is discharged from the chamber.

2. Apparatus for coking heavy hydrocarbons in fluid form, which comprises a metallic outer casing entirely surrounding a refractory lining, said metallic casing serving to prevent infiltration of air through said lining, said lining forming a horizontal coking chamber therein, said casing having openings at each end thereof, removable sealing means covering said openings, a substantially flat refractory floor for said chamber and heating flues below the floor and within the metallic casing, means for introducing into the chamber the heavy hydrocarbons to be coked, means for providing heated gases and vapors heated to above a coking temperature and for introducing them into the chamber, means for removing from the chamber vapors produced by the coking operation, a pusher ram and means for forcing it through the chamber to push out the coke, and means for receiving the coke after it is discharged from the chamber.

ROY S. PETERSEN.
